UNITED STATES PATENT OFFICE

STANLEY M. KENERSON, OF SPRINGFIELD, MASSACHUSETTS, ASSIGNOR TO STANDARD ELECTRIC TIME COMPANY, OF SPRINGFIELD, MASSACHUSETTS, A CORPORATION OF CONNECTICUT

ANNUNCIATOR

Application filed September 13, 1928. Serial No. 305,812.

This invention relates to annunciators, such as used in hospitals, barber shops, etc. to display any one of a series of numbers or other characters, and more particularly to the panel carrying the numbers, objects of the invention being to provide a panel which is smooth on its outer surface so as not to collect dust, which displays a number only when a light behind the number is lighted, which displays 5 each number sharply and distinctly when illuminated from the rear, which prevents interference between adjacent lights so that light from a lamp behind one number will not display adjacent numbers, which is 10 simple and economical in construction, which is durable in use and not easily broken, and which is generally superior to annunciator panels as heretofore constructed.

For the purpose of illustration, one concrete 20 embodiment of the invention is shown in the accompanying drawings, in which:

Fig. 1 is a front elevation of the annunciator;

Fig. 2 is an enlarged front elevation of a 25 part of the annunciator panel, with a portion broken away, and

Fig. 3 is a transverse section of the panel.

The particular embodiment of the invention chosen for the purpose of illustration 30 comprises a casing having a face portion 1 for attachment to a wall by means of screws 2, a door 3 hinged to the casing at 4, a panel 5 mounted in the door and carrying the aforesaid numbers, and a switch 6 for rendering 35 the lights (not shown) inoperative or to silence an associated buzzer (not shown).

The panel 5 comprises a back plate 7 of 40 metal or other opaque material having the numbers or other characters cut therethrough as indicated at 8. Mounted in the openings 8 flush with the face of the plate 7 are plugs 9 of transparent (or translucent) material such as celluloid, the plugs 9 preferably being 45 mounted with a cement which temporarily softens the surface of the celluloid. A coating 10 of thin translucent material is applied over the face of the sheet 7 and plugs 9. For hospital use the coating 10 preferably comprises white enamel (or paint) of such thickness 50 as to substantially conceal the openings

8 except when the lamp behind a particular opening is illuminated but not thick enough substantially to obstruct the visibility of the number when illuminated.

Such an annunciator panel presents a neat 55 appearance and by virtue of its smooth continuous surface it presents no recesses or ledges for the collection of dust, making it especially suitable for hospitals. Moreover, the numbers or other characters are wholly 60 concealed except when illuminated directly from the rear, thereby rendering the signals more legible in a well lighted location. Furthermore, light impinging on the rear face of a plug 8 at an angle is largely reflected or obstructed by the peripheral walls 65 of the plug opening, whereby each plug is substantially illuminated only by the light individual thereto.

I claim:

1. An annunciator panel comprising an opaque plate having openings therethrough in the form of characters, pieces of transparent celluloid fitting in said openings respectively flush with the face of said plate, and a thin 75 coating of enamel over said face which normally presents a uniform unbroken surface, but which is sufficiently translucent sharply to display the characters when the pieces are illuminated from the rear.

2. An annunciator panel comprising an opaque sheet having an opening therethrough defining a character, transparent material in said opening flush with the facing of said plate, and a thin coating of enamel over said 80 facing which normally presents a substantially uniform unbroken surface but which is sufficiently translucent sharply to display the character when said material is illuminated from the rear.

Signed by me at Boston, Massachusetts, this 90 fifth day of September, 1928.

STANLEY M. KENERSON.
